Primary Examiner — Lauren R Calve(74) *Attorney, Agent, or Firm* — Wells St. John P.S.(57) **CLAIM**

I claim the ornamental design for a door handle, as shown and described.

DESCRIPTION

FIG. 1 is a perspective view of a door handle according to the present design;

FIG. 2 is a second perspective view thereof;

FIG. 3 is a sectional view thereof, taken along lines 3-3 of FIG. 4;

FIG. 4 is a front view thereof;

FIG. 5 is a second sectional view thereof, taken along lines 5-5 of FIG. 3; and,

FIG. 6 is a third sectional view thereof, taken along lines 6-6 of FIG. 3.

The broken lines shown represent unclaimed matter and form no part of the claimed design.
